United States Patent

Des. 236,800

Patented Sept. 16, 1975

236,800

BOTTLE

John Pardo, 30 Roberts Lane, Yonkers, N.Y. 10701

Filed Oct. 9, 1973, Ser. No. 404,510

Term of patent 14 years

Int. Cl. D9—01

U.S. Cl. D9—111

FIGURE 5

FIGURE 6

FIGURE 7

FIGURE 8

FIG. 1 is a front elevational view of a bottle showing my new design;

FIG. 2 is a side elevational view thereof;

FIG. 3 is a bottom plan view thereof; and

FIGS. 4, 5, 6, 7, 8, 9, 10, and 11, are, respectively, cross sectional views to show the wall configuration at the planes 4—4, 5—5, 6—6, 7—7, 8—8, 9—9, 10—10, and 11—11, respectively.

The sides not shown are the same as the sides shown.

I claim:

The ornamental design for a bottle, as shown and described.
